(57) **CLAIM**

The ornamental design for a tablet computer, as shown and described.

DESCRIPTION

FIG. 1 is a front perspective view of a tablet computer showing my new design.

FIG. 2 is a rear perspective view of the tablet computer of FIG. 1.

FIG. 3 is a front view of the tablet computer of FIG. 1.

FIG. 4 is a rear view of the tablet computer of FIG. 1.

FIG. 5 is a left side view of the tablet computer of FIG. 1.

FIG. 6 is a right side view of the tablet computer of FIG. 1.

FIG. 7 is a top view of the tablet computer of FIG. 1; and,

FIG. 8 is a bottom view of the tablet computer of FIG. 1.

1 Claim, 7 Drawing Sheets
